UNITED STATES PATENT OFFICE.

WILLIAM H. K. BENNETT, OF CHICAGO, ILLINOIS, ASSIGNOR TO AMERICAN MANGANESE STEEL COMPANY, OF AUGUSTA, MAINE, A CORPORATION OF MAINE.

SUCTION NOZZLE.

1,423,165.

Specification of Letters Patent. Patented Aug. 8, 1922.

Application filed September 22, 1920. Serial No. 412,053.

To all whom it may concern:

Be it known that I, WILLIAM H. K. BENNETT, a citizen of the United States, and a resident of Chicago, in the county of Cook and State of Illinois, have made and invented 5 certain new and useful Improvements in Suction Nozzles, of which the following is a specification.

My invention relates to suction nozzles 10 such as are provided at the ends of the suction lines of sand and gravel dredges. In the operation of sand and gravel dredges and other similar apparatus it is customary to provide the end of the suction line with a 15 nozzle through which the liquid and accompanying sand and gravel may enter. In those instances, however, where a rotary or cutter nozzle is not used, considerable difficulty has been experienced due to the nozzle 20 becoming clogged, particularly where the dredging operations are taking place in a gravel deposit which contains considerable roots or other foreign material. This rapid clogging of the nozzle not only materially 25 limits the output of the dredge but often-times requires the suction line to be raised and the nozzle to be cleaned.

A further disadvantage of this particular 30 type of nozzle has heretofore been occasioned by the nozzle resting upon the top of the deposit and failing to work its way therein, particularly when the nozzle encounters a stone or other obstruction tending to block the path of the nozzle. It is accordingly an 35 object of my invention to provide a suction nozzle of the non-rotary type which will be capable of being operated under the most adverse circumstances without becoming clogged, it having been found that my improved 40 nozzle will efficiently and continuously operate in gravel deposits containing roots and other foreign material.

A further object is to provide a nozzle 45 which will at all times tend to dig and work its way into the deposit and pass over or around any obstruction which tends to block its path, this tendency for the nozzle to dig its way into the deposit resulting in the nozzle being able to displace any stones or 50 other obstructions which may have become temporarily located against the inlet openings of the nozzle.

A further object is to provide a nozzle 55 which is rugged and durable in construction and so designed that the inlet openings will

greatly exceed the capacity of the suction line, so that should one or more of the openings become temporarily clogged the remaining openings will be sufficient to take care of the requirements of the suction line. 60

A further object is to so construct the nozzle that the area of the inlet openings increase inwardly from the external surface of the nozzle, so that should any stones or other foreign material pass within the external 65 surface of the nozzle they will not become wedged within the inlet openings but will readily negotiate the remaining distance and enter freely into the suction line and, being necessarily restricted in size, will pass freely 70 through the pump.

With the foregoing and other objects in view, my invention consists in the improved suction nozzle for sand and gravel dredges 75 illustrated in the accompanying drawings and described in the following specification and in the combination and arrangement of parts and in the details of construction as hereinafter described and claimed, it being understood that changes may be made within 80 the scope of the claims without departing from the spirit of the invention.

The preferred embodiment of my invention is disclosed in the accompanying drawings, wherein:

Figure 1 is a view in vertical longitudinal section of my improved suction nozzle and adjoining fixture for securing it to a suction line;

Figure 2 is a bottom plan view of the nozzle proper;

Figure 3 is a view in vertical longitudinal section of a somewhat modified form of nozzle; and

Figure 4 is a view in section taken on the line 4-4 of Figure 3.

Referring specifically to the several views, wherein similar reference numerals designate corresponding parts throughout, the nozzle is composed of a base 10 which is 100 provided with suitable openings 11 for the reception of holding bolts 12 whereby the nozzle is secured to an elbow or adjoining fixture 13, which in turn is provided with suitable means for securing it to a suction 105 line. The nozzle is provided with the inclined bars 14 which are connected at their lower extremities to the base 10 and merge one into the other at their upper extremities so as to form the apex or digging end 110

15. The nozzle is thus formed with a conical shaped body and contains the tapering openings 16.

The bars are preferably bevelled inwardly, as more clearly illustrated in Figure 4, so that the nozzle openings 16 are bevelled inwardly as well as toward the base of the cone. The apex 15 is provided with the protruding and digging end which during the normal operation of the nozzle tends to force its way into the deposits and thus provide for the efficient action of the dredge. The bars terminate flush with the external edge of the base and should any large stones, sticks or foreign material tend to cling to the external surface of the nozzle due to the suction and inrushing water, they will be brushed out of the way as the nozzle forces its way into the deposit, thus moving the stones or other obstructions along its external surface toward and beyond the base.

The conical shape of the nozzle and the plurality of openings with which it is provided insures an inlet area largely in excess of the requirements of the suction line, so that should by any chance one or more of the nozzle openings become temporarily clogged the dredge will operate at its full efficiency due to the fact that the remaining openings of the nozzle will ordinarily be sufficient to take care of the requirements of the suction line. The obstructions, however, will be rapidly removed or displaced as the nozzle works its way into the deposit as above outlined.

I have illustrated the nozzle in use in connection with a 45° elbow or fitting 18 but it will be readily apparent that my improved nozzle may be secured directly to the suction line or to such other fittings as will bring the nozzle into the required position, depending upon the peculiar circumstances under which the nozzle may, at that time, be working.

The somewhat modified form of nozzle illustrated in Figure 3 is characterized by the fact that the base 17 partakes more of the nature of an ordinary flange and the bars which define the conical body of the nozzle protrude from and adjacent the inner edge of the flange, which nozzle I have found works most satisfactorily under certain conditions and although the outstanding flange of the base tends to prevent the

sliding of stones or other obstructions from the base of the nozzle, yet I have found that the action of the nozzle as it digs its way into the deposit will under certain conditions eliminate such obstructions. My improved nozzle is preferably formed as a single casting and, being composed of some hard wear-resisting material, such as manganese steel, will be rugged and durable and capable of rendering efficient and continuous service over a long period of time and, being entirely free of any moving or rotating parts, will require but little or no attention and will efficiently perform the service for which it is intended.

Having thus described and explained my invention, I claim and desire to secure by Letters Patent:

1. A suction line nozzle comprising a substantially conical shape body with inlet openings in the side wall thereof and an outlet opening through the base, and a digging point formed by the apex of the body.

2. A nozzle comprising a substantially conical shape body having inlet and outlet openings and a digging point at the apex thereof, and means for securing said body to a pipe line.

3. A nozzle comprising a base, a conical shape body carried thereby and provided with openings therein enlarging toward the base, said openings provided with inwardly diverging side walls, and means for securing the nozzle to a pipe line.

4. A nozzle comprising a base, a conical shape body carried thereby and provided with openings therein enlarging toward the base, said openings provided with inwardly diverging side walls, the apex of the body forming a digging point, and means for securing the nozzle to a pipe line.

5. A nozzle formed as a casting and comprising a base, means associated therewith for securing said base to a pipe line, outstanding bars carried by said base and merging at their upper ends to form a conical shape body, a digging point carried at the upper end of said body.

Signed at Chicago, in the county of Cook and State of Illinois, this sixteenth day of September, A. D. 1920.

WILLIAM H. K. BENNETT.
